Specification for Design.

Patented May 17, 1921.

Application filed January 12, 1921. Serial No. 436,838. Term of patent 14 years.

To all whom it may concern:

Be it known that I, HARRY I. SHIRE, a citizen of the United States of America, residing at Detroit, county of Wayne, and State of Michigan, have invented a new, original, and ornamental Design for Electrical Measuring Instruments, of which the following is a specification, reference being had to the accompanying drawing, forming part thereof.

The figure is a perspective view of an electrical measuring instrument showing my new design.

I claim:

The ornamental design for an electrical measuring instrument as shown.

In witness whereof I have signed this specification this 11th day of January, 1921.

HARRY I. SHIRE.
